CLAIM

The ornamental design for a lid, as shown and described.

DESCRIPTION

FIG. 1 is top plan view of a lid showing the new design;
FIG. 2 is a top perspective view of the lid design;
FIG. 3 is a side elevational view of the lid design;
FIG. 4 is a bottom plan view of the lid design; and,
FIG. 5 is a bottom perspective view of the lid design.
In the drawings, the broken lines showing portions of a lid
depict environment and form no part of the claim.
